GRID STRUCTURE FOR CATHODE-RAY TUBES

Donald R. Core, Oakland, Calif., assignor to Chromatic Television Laboratories, Inc., New York, N. Y., a corporation of California

Application May 26, 1955, Serial No. 511,150

8 Claims. (Cl. 313—78)

This invention relates to cathode-ray tubes especially adapted for color television image production. It is particularly related to an improved assembly and support for securing and supporting a color-control grid structure, or additional grid structures as well, within the tube envelope and in the tube wall. The support mechanism provides also for ready alignment of the supported grid structure relative to the phosphor-coated target element, whether that element be a separately supported target plate, or whether it be a phosphor coating applied directly to the inner surface of the tube face panel.

Various forms of color television tubes for producing images for direct viewing have been proposed in the art. Among the tube types which are proving to be particularly satisfactory is one utilizing a multiplicity of generally parallelly positioned substantially uniformly spaced linear conductors arranged in coplanar relationship to form a so-called color-control grid structure. The color-control grid structure is adapted for positioning substantially adjacent to a final target upon which the color television image appears at times of excitation of the target surface by one or more impinging cathode-ray beams appropriately modulated under the control of video signal information.

This type of structure utilizes as a color-control grid a plurality of linear conductors of which, for the so-called single gun type of tube (that is, a tube in which a single cathode-ray beam only is projected from an electron gun to impact the target), adjacent linear conductors are maintained electrically insulated from each other and alternate conductors are electrically connected. For a tube of the type utilizing a plurality of cathode-ray beams to impact the target area, the various linear conductors of the color-control grid may all be electrically connected.

The tube type here being considered has provided on the target surface upon which the cathode-ray beam finally impinges after it is directed through and between the linear conductors of the color-control grid a series of phosphor strips of different light producing characteristics. For tricolor operation, that is, where the final color television image is produced as an additive representation resulting from activation of phosphor strips to produce the image in three separate colors, the phosphor strips are formed to produce light, preferably in the colors red, green and blue. The phosphor strips are arranged according to a selected repeating pattern or color cycle. Illustratively, the phosphor strips may be of such characteristics as to produce light in color sequence of red, green, blue, green, red, green, etc., when the signal modulated cathode-ray beam is directed thereupon.

In the usual form of arrangement of a color television tube of this character, the phosphor strips to produce the different colors of light are so arranged that phosphor strips to produce one selected color of light, say, green, are electron-optically centered with respect to adjacent linear conductors. All phosphor strips of

this character also extend substantially parallel to the linear conductors of the color control grid. The phosphor strips to produce the light in the other two colors of the tricolor are, generally speaking, electron-optically centered beneath the linear conductors. Consequently, if the phosphor coating of the target is covered with a thin metallic film, such as an electrically conducting aluminum film, so that a high potential may be applied between this film and the electron source, and if the color-control grid is maintained at approximately the potential of the so-called G_3 electrode (also frequently called the anode) of the electron gun, a strong electrostatic field will be maintained between the color-control grid and the final target and acceleration of the scanning cathode-ray beam will occur in the region between the color-control grid and the target. The field also tends to refocus the electron beam directed from the electron gun to the color control grid, so that the beam is brought to a sharper spot at the plane of the phosphor-coated target. At times when the linear conductors of the color-control grid are all at the same potential with respect to each other, the cathode-ray beam directed to the target through the color-control grid will be focused at a sharply defined spot on that target strip which is electron-optically centered in the space between adjacent linear conductors through which the cathode-ray beam is directed. On the other hand, if one or the other of the linear conductors of the color-control grid is maintained at a higher potential (more positive) than the other, the electron beam passing adjacent thereto and between the linear conductors is not only accelerated toward the target but it is also deflected in the direction of the more positive voltage, in which case light is produced in a different color by what is known as a microdeflection of the scanning cathode-ray beam.

The foregoing features are generally known in the art. Accordingly, it will be appreciated that this invention is not broadly directed to the control of the color image reproduction but, rather, is concerned particularly with the support of the color-control grid structure formed of the plurality of linear conductors, each substantially uniformly spaced from the other, and all arranged substantially parallel to each other, and in coplanar relationship. It has been found in connection with a color-control grid of this character, that the support for the grid, since the linear conductors must all be kept taut if vibration and a resultant lack of color fidelity of the image is to be avoided, is frequently heavy and cumbersome, and adds considerably to the cost of manufacturing tubes, since the support for the linear conductors of the color-control grid usually is a rather heavy frame.

The present invention provides for the support of the linear conductors of the color-control grid directly in the tube wall, and thus provides for a cathode-ray tube construction in which the weight is greatly reduced, the structure greatly simplified, the opportunity to provide extremely tightly strung linear conductors, and offers the opportunity of obtaining increased image area. At the same time there is no frame mass held or suspended within the tube envelope.

In addition, the construction of the present invention offers an opportunity to reduce materially the components within the evacuated volume of the cathode-ray tube, and thus provides an easier way to withdraw gas from within the tube. Still further, the present invention will be found to provide ready means to supply switching potentials to adjacent linear conductors of the color control grid. The shielding problem is also simplified and can be supplied externally of the tube.

Therefore, included among the objects of the invention are those of providing greatly improved support struc-

ture for the color-control grid, an improved tube structure from the standpoint of weight, a rigidity of the color-control grid frame and its components, and a greatly simplified evacuation process.

Other objects, of course, involve the production of a color television cathode-ray tube offering increased opportunities for large size images and an opportunity more readily to aline the linear conductors of the color-control grid with the phosphor coated strips upon which the image is to be realized.

Other objects of the invention will, of course, suggest themselves to those skilled in the art to which it is directed, upon reading of the following description and claims in connection with the accompanying drawings wherein:

Fig. 1 is a fragmentary sectional view of a portion of television tube incorporating the features of this invention; and

Fig. 2 is an enlarged sectional view showing particularly the arrangement of tube components and the sandwich construction for securing the linear conductors of the color-control grid.

Referring now to the drawings for a further understanding of the invention, the cathode-ray tube envelope of the type herein to be described comprises the usual flattened end wall through which the images are usually viewed, and then usually a funnel or conical-shaped portion merging into a tube neck, in which there is contained the sources to develop the flow of the scanning cathode-ray beam or beams. These components are known in the art as the electron gun and comprise the source to release the electrons, an appropriate control or modulating electrode and one or more accelerating or anode electrodes which are collectively known as the electron gun (not shown). About the tube neck, and usually positioned at about the point where the funnel or conical-shaped tube wall merges with the neck, there may be positioned suitable deflecting coils for deflecting the developed cathode-ray beam and causing it to sweep the target area of the tube to trace a raster, which is viewed through the flattened end wall.

In the alternative, electrostatic deflecting means may be contained within or without the tube or there may be a combination of electrostatic or electromagnetic means. Where additional focusing over and above that electrostatically achieved by the application of suitable potentials to various electrode elements within the tube is required, suitable electromagnetic focusing coils may also be used. Combinations of this sort are well known, and are not illustrated herein for sake of convenience.

As the tube herein to be described is formed, it comprises a face panel 11 in the form of a glass or transparent vitreous member through which the produced image may be viewed from the direction indicated by the arrow external to the tube. The face panel is formed generally flattened, and of a periphery configuration which may be circular or which may closely approach rectangular form, depending, of course, upon the type of tube manufactured. The inner surface of the face panel may, for some tubes, be coated with the phosphor adapted to produce the image upon being excited and impacted by the scanning cathode-ray beam, or the face panel may be left clear and the image may be produced upon a separate phosphor coated plate 15, as will later be described in more detail. The face panel of the present construction is formed in generally dish-shaped configuration with the flattened portion 17 providing the viewing area, and the upturned portions 18 providing a more or less tubular section which is adapted to be secured to the funnel section of the tube envelope. The funnel section 19 of the tube likewise is provided for connection to the end of the tube and to be secured directly to or through to the intermediate components to the upturned portion 18 of the face plate 11.

The invention herein to be described provides partic-

ularly for supporting and mounting a multiplicity of linear conductors of the character above described so as to provide the supporting frame work directly in the tube wall. To this end a multiplicity of parallelly strung linear conductors or grid wires 21 are caused to span the interior of the tube envelope and to extend for approximately the distance across the ring-like upturned edges 18 of the face plate. As is well known, grid conductors of this sort are usually formed of fine wire of the order of about 3 mils, although this is not to be considered as a limiting statement, but rather illustrative, and are spaced apart by spacings appropriate to the size of the tube and the image size to be developed. Illustratively, for a so-called 21 inch tube size and with the grid conductors spaced at approximately 700 mils from the phosphor coated target, the wire spacing may be of the order of 25 mils. All of the conductors 21 of the color-control grid are preferably held in co-planar arrangement and extend as above stated, to overlap the upturned edges 18 of the face panel dish. Preferably, in the fabrication of the tube, the conductors are strung prior to tube assembly, so as to overlap a metallic ring-like member 23, the surfaces of which are ground flat for ready sealing and parallel to one or more suitable, plate mounting pins. The wires extend parallel to the mounting pins in the preferred construction.

The configuration of the ring-like member is such that it also corresponds substantially to the periphery of the tube, and it is of a cross section such that the plate extends slightly within the inner boundary of the upturned edges 18 of the dish-like face panel and also slightly beyond the outer periphery thereof. After the grid conductors are appropriately spaced and tightly stretched across the ring-like member 23, they are caused to rest on glass frits 25 to separate them and insulate them from the metallic ring-like member 23. Then, with the conductors so stretched and resting upon the glass frits 25, other glass frits 27 are placed thereover and a second metallic ring-like member 29 is rested upon the so assembled components. With the linear conductors of the color-control grid so stretched and so positioned, and the ring-like members 29 and 23 held closely together, the assembly is heated to the point where the glass frits become plastic and imbed the linear conductors and at the same time adhere to the surface of the linear conductors and produce a bond with the metallic ring-like members 23 and 29. The glass frits have a high melting temperature by which is meant that they melt at a temperature higher than any temperature experienced in the tube evacuation and bakeout. Consequently, when the linear conductors of the color-control grid are passed through the glass frits and the frits are fused to become a glass seal, there is a bond formed between the adjacently positioned metallic ring-like members 23 and 29 and a grid support sandwich is formed. At this or a later time the linear conductors of the grid which protrude beyond the sandwich edge shown at 31 can be connected together if desired, or the connections may be established prior to the sealing operation. So-sealed and so-formed, the sandwich holds the linear conductors of the color-control grid securely. There has been established a bond between the wires and the support which will be vacuum-tight when the tube is exhausted. The assembly is ready, at this point, for mounting, together with the tube face panel section and the funnel section, to form the complete tube wall assembly.

For purposes of convenience and in order to establish a tight connection between the upturned edges 18 of the face panel and the color-control grid support sandwich, there may be secured a flange 33 having a flattened surface of a form substantially matching that of the metallic ring-like member 29 of the color-control grid support sandwich. The tube may be provided as either glass or metal bulbs, for instance, and where the bulb is glass there may or may not be a metal flange. The securement of the glass face panel section to such a metal flange may be accomplished in any desired fashion as is

well known in the art. When the flange has been secured, the face panel may then be supported against the metallic ring-like member 29 with suitable glass frits of lower melting temperature therebetween. When the components are heated, the glass frits are caused to become plastic, after which the heat is removed and, upon cooling, the glass frits form a glass seal between the flange 33 and the metallic ring-like member 29. Similarly, the funnel-shaped section 19 of the tube, if formed of a metal, may have its outermost edge 35 also formed into a flange-like element of a shape generally complementary to the flange 33. If the funnel-shaped section is of metal, it may be machined to provide the outer flange. This flange is then matched and rested against the ring-like flange 23 of the color-grid support sandwich and by means of a bond provided by the glass frits shown at 37 may be secured to the color-control grid sandwich. Thus, the color-control grid sandwich when appropriately secured, as explained, to the upturned edges of the face panel and to the funnel section of the tube wall, forms a section of the tube wall and is completely merged therewith. The conical or funnel-shaped tube wall then may be provided with a conducting coating 39 (in the case of the glass tube) for the application of suitable potentials thereupon. This coating is usually of a carbon type, such as that known as "Aquadag." The panel wall also has a very slightly conducting coating 40 applied thereto. This latter coating may be in the form of an iron oxide (FeO) or a chrome oxide on the inside of the face panel.

In the case of a tube of the sort in which the image is caused to appear on surface other than the face panel, a phosphor plate of the character illustratively shown at 15 is provided within the tube. To this end there is formed within the tube wall and supported therein a plurality of support pins 41 and 42 to which is attached a suitable phosphor plate-supporting bracket in the form of a U-shaped element 43. Illustratively, the U-shaped element is arranged to extend at generally uniformly spaced locations with respect to the interior wall of the tube as formed by the upturned portion 18 of the face panel, so that if, for instance, the tube is of a sort such that the upturned section 18 follows a circular path, the U-shaped section 43 will also follow a circular path and extend throughout an arc of a circle sufficient to hold the edges of the phosphor plate 15 or the U-shaped section may be short length sections so that the phosphor plate edges may be held at spaced locations. Where the tube is formed to provide a viewing area more closely rectangular in shape than the U-shaped brackets, it may conform more closely to one side of a rectangle. The phosphor plate 15 is then positioned within the bracket prior to the assembly of the color-control grid with the upturned edges of the face panel. The connection shown by the conductor 47 extending through the tube wall is to provide high voltage which may be connected at the terminal point 48. The plate 15 so formed is coated with phosphor adapted to fluoresce or become luminescent to electron beam excitation as above explained. The phosphor is coated with aluminum or other suitable metallic film conventionally represented at 49, and high voltage is applied to the film. As is well known, the electron beam from the electron gun which has been diagrammatically shown in the figure by the dot-dash line passes adjacent to and between the conductors of the color-control grid to impact the phosphor-coated plate 15 of the face panel, as likewise explained. For the purpose of providing voltage on the conductors of the color-control grid, the adjacent wires are maintained electrically insulated from one another by the seal formed by the fusion of the glass frits. Alternate conductors of the color-control grid are electrically connected. Appropriate potentials may be applied to these conductors and there may then be superimposed upon this steady potential an oscillatory potential to cause the scanning cathode-

ray beam to oscillate in its motional path so that it is caused to impinge upon the phosphors to produce light in the different colors in controlled manner. Oscillations of the scanning cathode-ray beam for conditions where colored images are produced according to standards established at present in the United States by the Federal Communications Commission may use an oscillation of the order of 3.58 megacycles per second, which oscillation is then provided by the connection of the high frequency coil shown at 53 to which the oscillatory voltage from any appropriate source, not shown, is applied. A shielding housing 55 is secured to the outer edge of the support sandwich for the color-control grid and surrounds the coil 53 electrically to shield the oscillations from having an external effect.

The foregoing description, particularly for purposes of simplified explanation, treats the invention and its specific embodiment in the nature of a color-control grid structure of a sort wherein the separate linear conductors are parallelly positioned with respect to each other and are all arranged in substantially coplanar fashion with respect to each other. However, as is known in the art, it is advantageous in some tube types to have the linear conductors of the color-control grid maintained in parallel relationship to one another but, in addition, located along a generally cylindrical path at readily determinable distances from one or more points in space. This form of grid does not permit of a strictly coplanar relationship of the linear conductors with respect to each other. Grid structure of the sort last mentioned are known in the art as cylindrical grids and are particularly useful in tube types where a high degree of correction of the sort known in the art is desired and where the angle of deflection of the cathode-ray beam is very large. It will be apparent that the construction herein shown for providing the sandwich within which the linear conductors of the color-control grid are held may readily be of such peripheral shape and configuration as to provide for holding the cylindrical type color-control grid structure as well as the planar type color-control grid structure.

In addition, for purposes of simplified explanation, it has been particularly indicated herein for description purposes that the phosphor coating on the impacted target area shall be upon the plate 15, but, as is hereinabove noted, it is frequently desirable for direct viewing and in some type of tube envelopes that the inner surface of the face panel 11 shall be coated with phosphors and that the resultant image shall appear to the viewer directly upon the inner surface of the face panel which is viewed. In this event, plate 15 and its coating may be omitted and the phosphor coating and the associated conducting metal film will then be placed upon and supported upon the inner surface of the face plate forming the end of the tube envelope. It is, therefore, intended that in the definition of the invention as presented in the claims hereinafter appended the construction shall be broadly interpreted unless otherwise limited by specific claim terminology.

From the foregoing it will be apparent that the so-called sandwich to support the grid wires is positioned slightly closer to the source of the electron beam or cathode-ray beam than is the target area upon which the images are to appear. Consequently, it will be borne in mind that the internal opening provided in the ring-like members 23 and 29 may be slightly less than the area of the image which is to be developed at the target, due, of course, to the angle at which the electron flow from the tube electron gun structure is directed toward the target. Alternatively, the area may be equal to the target area on which the image is to appear, or, if desired, it could be slightly larger. Accordingly, in the claims, reference to the relative dimensions of the central opening in the rings with respect to the target area when defined as approximately the same will be understood in accordance with this description.

Having now described the invention, what is claimed is:

1. A cathode-ray tube for color television comprising a grid support frame consisting of a pair of support rings each having a central opening of area and configuration generally corresponding to that of an image to be produced within the tube for viewing, a multiplicity of tautly strung parallelly positioned linear conductors overlapping opposite edges of the support rings and located therebetween, a glass seal between the support rings imbedding the overlapping linear conductors and serving for sealing the support rings to each other in sandwich fashion and for anchoring the tautly strung conductors between the support rings in sandwich fashion, a face panel and a funnel section, means to seal and secure the face panel to one outer surface of the sandwich supporting the linear conductors and means to seal the funnel section to the opposite outer surface of the sandwich supporting the linear conductors to provide a tube wall section which will be vacuum-tight upon tube exhaust.

2. A cathode-ray tube for color television comprising a grid support frame consisting of a pair of support rings each having a central opening of area and configuration generally corresponding to that of an image to be produced within the tube for viewing, a multiplicity of tautly strung parallelly positioned coplanarly arranged linear conductors overlapping opposite edges of the support rings and located therebetween, a glass seal between the support rings imbedding the overlapping linear conductors and serving for sealing the support rings to each other in sandwich fashion and for anchoring the tautly strung conductors between the support rings in sandwich fashion, a face panel and a funnel section, means to seal and secure the face panel to one outer surface of the sandwich supporting the linear conductors and means to seal the funnel section to the opposite outer surface of the sandwich supporting the linear conductors to provide a tube wall section which will be vacuum-tight upon tube exhaust.

3. A cathode-ray tube for color television including a face panel, a funnel section adapted for securement to the face panel about its peripheral edge, a color-grid support frame comprising a pair of support rings, a multiplicity of substantially uniformly spaced and tautly held substantially parallelly positioned linear conductors overlapping opposite edges of the support rings and frit means having a melting point higher than any temperature produced during evacuation and bake-out of the tube held between the support rings and adapted upon heating to a plastic state to imbed the overlapped linear conductors and to adhere to the rings and the conductors and subsequently when cooled to a solid state to secure and seal the support rings to each other in vacuum-tight manner and to anchor the grid wires between the support rings in sandwich fashion, and glass frit means for securing the face panel and the funnel section of the tube components to the outer surfaces of the color grid support sandwich.

4. The tube claimed in claim 3 comprising, in addition, means to establish electrical connection to the color-grid linear conductors sealed between the sandwiched ring-like members, means to connect electrically the conductors of the color-grid so that alternate conductors are electrically connected and adjacent conductors electrically insulated from each other to form the grid conductors into two electrically separate sets, means to introduce high frequency oscillations between adjacent conductors and shielding means surrounding the means to provide high frequency oscillations.

5. The tube claimed in claim 3 comprising, in addition, a flat ground metal ring secured to the edge of the dishlike face panel, a second flattened metallic ring secured to the edge of the funnel member and glass frit means to secure the metal rings to the metal rings of the grid conductor support sandwich.

6. A cathode-ray tube for color television including a

face panel, a funnel section adapted for securement to the face panel about its peripheral edge, a color-grid support frame comprising a pair of similar support rings in generally peripheral engagement, a multiplicity of substantially uniformly spaced coplanar parallelly and tautly held linear conductors spanning the open central areas of the support rings and each overlapping the ring edges, glass sealing means having a melting point higher than the temperature produced during evacuation and bake-out of the tube for securing the support rings and anchoring the linear conductors between the said support rings in sandwich fashion and glass sealing means for securing the face panel and the funnel section of the tube components to opposite outer surfaces of the linear conductor support and anchoring sandwich.

7. A cathode-ray tube for color television comprising a face plate section of dish-like formation having a generally flattened window area and upturned edges sectionally forming a ring-like pattern, a funnel shaped bulbous portion for the tube also having a ring-like cross section of substantially like form and adapted for securement with the dish-like face panel, a grid conductor support sandwich comprising a pair of flattened ring-like members of peripheral configuration substantially corresponding to the ring-like formation of the funnel and face plate sections, a multiplicity of tautly strung grid conductors and generally uniformly spaced in parallel relationship to each other and located between the flattened ring-like members, glass sealing means sandwiched between the flattened ring-like members between which the grid conductors are passed and which sealing means upon being heated to a plastic state flows around the conductors and which, upon cooling, solidifies and forms a bond between the ring-like members and an anchor for securing the tautly strung grid conductors between the frame sections, the said glass seal having a melting point higher than any temperature produced during tube evacuation and bake-out, and glass sealing means for securing the face panel and the funnel section to the outer surfaces of the ring-like sandwiched support members.

8. A cathode-ray tube for color television comprising a face plate section of dish-like formation having a generally flattened window area and upturned edges sectionally forming a ring-like pattern, a funnel shaped bulbous portion for the tube also having a ring-like cross section of substantially like form and adapted for securement with the dish-like face panel, a grid conductor support sandwich comprising a pair of flattened ring-like members of peripheral configuration substantially corresponding to the ring-like formation of the funnel and face plate sections, a multiplicity of tautly strung grid conductors arranged in coplanar array and generally uniformly spaced in parallel relationship to each other and located between the flattened ring-like members, glass sealing means sandwiched between the flattened ring-like members between which the grid conductors are passed and which sealing means upon being heated to a plastic state flows around the conductors and which, upon cooling, solidifies and forms a bond between the ring-like members and an anchor for securing the tautly strung grid conductors between the frame sections, the said glass seal having a melting point higher than any temperature produced during tube evacuation and bake-out, and glass sealing means for securing the face panel and the funnel section to the outer surfaces of the ring-like sandwiched support members.
